Primary Examiner — Marissa J Cash*Assistant Examiner* — Rebecca Tsehayé(74) *Attorney, Agent, or Firm* — Fox Rothschild LLP(57) **CLAIM**

The ornamental design for an electric arc lighter, as shown and described.

DESCRIPTION

FIG. 1 is a front perspective view of the electric arc lighter of the present invention.

FIG. 2 is a top view of the electric arc lighter of FIG. 1.

FIG. 3 a bottom view of the electric arc lighter of FIG. 1.

FIG. 4 is a left side view of the electric arc lighter of FIG. 1.

FIG. 5 is a right side view of the electric arc lighter of FIG. 1.

FIG. 6 is a front end view of the electric arc lighter of FIG. 1; and,

FIG. 7 is a rear end view of the electric arc lighter of FIG. 1.

The broken lines in the drawings depict portions of the electric arc lighter that form no part of the claimed design.

1 Claim, 5 Drawing Sheets(56)
